TELEPHONE AMPLIFIER

Jack J. Zimmerman, 143 S. Delaplaine Road,
Riverside, Ill.

Filed Mar. 19, 1963, Ser. No. 74,038

Term of patent 7 years

(Cl. D26—14)

FIGURE 1 is a perspective view of a telephone amplifier, showing my new design;

FIGURE 2 is a side elevational view, the opposite side being substantially a mirror image thereof;

FIGURE 3 is a rear elevational view; and

FIGURE 4 is a cross sectional view, taken substantially on the line 4—4 in FIGURE 1.

The broken showing of a handset in FIGURE 2 and legible matter in FIGURE 1 is for illustrative purposes only. A portion of FIGURE 1 is diagonally lined to indicate transparency.

I claim:

The ornamental design for a telephone amplifier, substantially as shown and described.
